Claims priority, application Great Britain, June 4, 1962, 21,493/62

16 Claims. (Cl. 239—15)

This invention relates to pneumatic electrostatic spraying coating of objects with liquids, and particularly to pneumatic electrostatic spray painting.

The present invention consists in pneumatic electrostatic spraying apparatus wherein the liquid to be sprayed is discharged under pressure into a vortex of gaseous fluid, means being provided to electrostatically charge the liquid at or before its point of discharge into the vortex.

The liquid may be discharged through a first nozzle opening disposed coaxially within a second nozzle opening which is annular and through which the gaseous fluid is discharged to produce a gaseous vortex which atomizes the liquid discharged through the first nozzle opening and carries along with it the atomized liquid particles towards the object to be coated, the charged particles being attracted to the object by reason of the electrostatic charge thereon. Both nozzle openings may be formed in the same nozzle device.

The liquid is preferably discharged as a thin divergent conical film of liquid which is coaxial with the axis of the gaseous vortex.

In order that the invention may be more clearly understood, various embodiments thereof will now be described with reference to the accompanying drawings, in which:

FIGURE 1 is a longitudinal axial sectional view, with certain portions shown in elevation, of one embodiment of portable hand spray gun according to the invention, together with a perspective representation of a supply of spraying material,

FIGURE 2 is an axial section on a larger scale of the atomizing and spraying head of the gun shown in FIGURE 1,

FIGURE 3 is a transverse section on the lines A—A' in FIGURE 2,

FIGURE 4 is a transverse section on the lines B—B' in FIGURE 2,

FIGURE 5 is an axial section of the spraying head portion of another embodiment of a spraying apparatus according to the invention, and

FIGURES 6, 7 and 8 are fragmentary axial sectional views showing further embodiments of the nozzle.

Referring now to FIGURE 1, there is shown a hand spray gun embodying the present invention and comprising a barrel portion 101 and hand grip portion 102. A detachable spraying head T is mounted at the end of the barrel portion 101. The spraying head T may be supplied with compressed air through a passage 103 in the barrel portion and also have a high D.C. voltage applied thereto by means of a high tension cable 104 also extending through the barrel portion. The air supply line and high tension cable pass up through the hand grip portion of the gun. A finger operated trigger 105 is connected to a rod 106 also passing through the barrel of the gun, and operation of the trigger controls the ejection of the paint or other liquid to be sprayed from the head T, as will hereinafter be described. The paint or other liquid to be sprayed is supplied under pressure from a container 107 through a pipe 108 to the spray head T.

The spray head T will now be further described with

reference to FIGURES 2 to 4 of the drawings. In these figures the spray head T comprises a housing 1 in the front end of which is screwed a nozzle head 2 having a coaxial bore 3 extending therethrough, the bore being enlarged adjacent its outer end to form a cylindrical chamber 4 having the inner surface of its outer end wall tapering to a hole having a sharp edge 5 and of smaller diameter than the bore 3. Extending into the chamber 4 and substantially tangentially to the peripheral wall thereof are a plurality of passages 6 which connect with an annular groove 7 around the body of the head 2, the groove connecting with the interior of the housing 1 by grooves 8 in the body of the head 2 which extend in directions parallel to the axis thereof.

10 A nozzle 9 with a tapered end 10 is fitted in the bore 3 and has a central passage 17 serving for the supply of the paint or other liquid to be sprayed to the nozzle, and within the passage is located a pin 18 having a conical head 19 adapted to seat in a conical recess 20 at the front end of the passage 17. The pin 18 has a stem 21 of reduced diameter adjacent the head 19. Extending radially from the stem 21 and spaced from the head 19 are longitudinal ribs 22 for locating the head centrally with respect to the passage 17. The passage is enlarged at 23 and is provided with a connection 24, 25 from pipe 108 through which the liquid to be sprayed fed from the container 107 can be supplied under pressure to the passage 17. The washer 27 secured by screw 28 forms a seal at the rear end of the passage. Longitudinal adjustment of the pin 18 is effected by means of the trigger 105 through the rod 106. The rear end of the pin is threaded at 26 for connection to the rod 106. The head T is fixed to the barrel portion 101 by the screws 29 which also pass through a flange 30 on the nozzle 9.

20 The high D.C. voltage is fed through the cable 104 to a resistor 31 connected through a spring 32 to a block 33 of high resistivity material directly in contact with the coating liquid in the connection 24.

25 With the exception of the high tension cable 104, the spring 32 and the highly resistive block 33, all of the parts of the barrel 101 and the head T may be made of electrical insulating material, or alternatively the pin 18 may be made of a conducting or high resistance material and be connected to the high voltage source and serve 30 as the electrode for charging the liquid as it is discharged from the device.

In operation, compressed air is fed through the passage 103 to the housing 1, and on entering the chamber 4 through the passages 6, produces a rapidly rotating mass 50 of air and a vortex upon discharging through the annular gap between the end 10 of the nozzle 9 and the edge 5. Paint or other liquid is discharged under pressure through the annular gap between the conical head 19 and the end 10 in the form of a thin divergent conical film of 55 liquid, coaxial with the axis of the air vortex, and distributed in the gases of the vortex, which atomizes the liquid. The liquid is electrostatically charged as it is discharged within the vortex.

FIGURE 5 is a sectional view of a further embodiment 60 of spray head in which it is possible to adjust the annular gap through which the compressed air vortex passes.

Longitudinally slidable in the bore 3 is a nozzle adjuster 39 having a tapered end 10 which projects into the hole defined by the sharp edge 5, the taper of the end 10 65 being more acute than the taper of the end wall of the chamber 4, so that the annular gap between the tapered end 10 and the chamber end wall can be varied by axial adjustment of the adjuster 39. This is effected by rotation of the member 11 threaded on to the end 12 of the adjuster 39 which projects out of the rear end of the housing 1, the intermediate part 13 of the adjuster 39 sliding 70

through a hole in the rear of the housing and being surrounded by a thick washer 14 of resilient material, such as rubber, which is compressed between the internal surface of the rear wall of the housing and a collar 15 screwed on to the intermediate part 13 of the adjuster. The washer 14 serves both for preventing leakage of air through the rear of the housing and also for holding the adjuster 39 forwardly in accordance with the adjustment of the member 11. Between the member 11 and the back of the housing there are located ball bearings 16. The pin 18 is also longitudinally adjustable by means of the knob 40 secured in adjustable position by means of a counter screw 41 on the rear end of the pin 18. The compressed air inlet is shown at 42 and the inlet for the coating liquid at 43. This spray head may form part of either a fixed or portable apparatus.

FIGURES 6, 7 and 8 show some modified shapes which the end of the passage 17 and the end of the pin 18 may have, instead of the conical shape described above.

Whilst particular embodiments have been described, it will be understood that various modifications may be made without departing from the scope of the invention. For example, the adjuster 39 may constitute a hollow electrode for charging the liquid in addition to or instead of the pin 18. The electrode may be made of high resistance material, or be made of insulating material with a coating of a high resistance material in contact with the liquid. In another embodiment, if the liquid itself is sufficiently conducting, all the parts exposed at the front of the device may be made of insulating material, the liquid being in contact with an electrode as it flows towards the discharge nozzle and the liquid particles becoming electrostatically charged as they are released into the vortex.

Whilst the device shown is in the form of a hand spray gun, the features of the invention can also be incorporated in a fixed spraying installation.

I claim:

1. Electrostatic spraying apparatus, comprising a supply of coating material, first nozzle means communicating with said supply for discharging particles of said material along a first path, said first nozzle means including means for directing the individual particles of said material in substantially linear directions along said first path, means for electrostatically charging said material prior to its discharge from said first nozzle means, a source of fluid under pressure, and second nozzle means connected to said source for producing a vortex of said fluid and for discharging said vortex along a second path intersecting said first path, said first nozzle means discharging the linearly moving particles of material into said vortex to thereby atomize said material.

2. Apparatus for coating objects with a supply of coating material, comprising first nozzle means communicating with said supply for discharging particles of coating material therefrom along a first path, said first nozzle means including means for directing the individual particles of said material in substantially linear directions along said first path, means electrically connected to said first nozzle means for electrostatically charging said material, and second nozzle means operatively associated with said first nozzle means for producing a vortex of gaseous fluid and for discharging said vortex along a second path intersecting said first path, said first nozzle means discharging the linearly moving particles of material into said vortex to thereby atomize said material.

3. Electrostatic spraying apparatus, comprising a supply of coating material, first nozzle means communicating with said supply for discharging particles of said material along a first path, said first nozzle means including means for directing the individual particles of said material in substantially linear directions along said first path, means for electrostatically charging said material, a source of fluid under pressure, and second nozzle means connected

5 to said source and operatively associated with said first nozzle means for producing a vortex of said fluid and for discharging said vortex along a second path, said second path intersecting said first path at an acute angle, said first nozzle means discharging the linearly moving particles of material into said vortex to thereby atomize said material.

4. Apparatus for coating objects with a supply of coating material, comprising a nozzle head having a discharge chamber therein, first nozzle means positioned within said discharge chamber and communicating with said supply for discharging a spray of material therefrom along a first path, means for electrostatically charging said material prior to its discharge from said first nozzle means, a source of fluid under pressure, and conduit means interconnecting said source of fluid and said discharge chamber for producing a vortex of said fluid, said nozzle head and said first nozzle means forming second nozzle means for discharging said vortex from said chamber along a second path intersecting said first path, said first nozzle means discharging the charged material into said vortex to thereby atomize said material.

5. Electrostatic spraying apparatus for coating objects with a supply of coating material, comprising a nozzle head having a discharge chamber therein, first nozzle means movably positioned within said discharge chamber and communicating with said supply for discharging a spray of said material along a first path, means electrically connected to said first nozzle means for electrostatically charging said material prior to its discharge from said first nozzle means, a source of fluid under pressure, conduit means interconnecting said source of fluid and said discharge chamber for admitting said fluid thereto, said nozzle head and said first nozzle means forming second nozzle means for discharging said fluid from said chamber along a second path intersecting said first path, said first nozzle means discharging the charged material into said fluid to thereby atomize said material, and means for moving said first nozzle means relative to said discharge chamber to vary the rate of discharge of said fluid therefrom.

6. Electrostatic spraying apparatus for coating objects with a supply of liquid coating material, comprising a nozzle head having a discharge chamber therein, first nozzle means movably positioned within said discharge chamber and communicating with said supply for discharging a spray of said material along a first path, means for electrostatically charging said material, a source of gaseous fluid under pressure, conduit means interconnecting said source of fluid and said discharge chamber for producing a vortex of said fluid, said nozzle head and said first nozzle means forming second nozzle means for discharging said vortex from said chamber along a second path intersecting said first path, said first nozzle means discharging the charged material into said vortex to thereby atomize said material, and means for moving said first nozzle means relative to said discharge chamber to vary the rate of discharge of said fluid therefrom.

7. Apparatus for coating objects with a supply of coating material, comprising a nozzle head defining a first bore having a discharge chamber adjacent one end thereof, first nozzle means positioned in said first bore and having a second bore communicating with said supply of coating material for discharging material from said supply along a first path, means for electrostatically charging the material in said second bore, a source of fluid under pressure, and conduit means interconnecting said source of fluid and said discharge chamber for admitting said fluid thereto, said nozzle head and said first nozzle means forming second nozzle means for discharging said fluid along a second path intersecting said first path, said conduit means including at least one passage extending substantially tangentially into said discharge chamber for producing a vortex of the fluid discharged from said second nozzle means, said first nozzle means

discharging the charged material into said vortex to thereby atomize said material.

8. Apparatus of the character set forth in claim 7, in which said first nozzle means is of electrically insulating material.

9. Apparatus for coating objects with a supply of liquid coating material, comprising a nozzle head defining a first bore having an enlarged chamber adjacent one end thereof, said nozzle head including a wall portion between said enlarged chamber and said one end forming a restricted discharge outlet from said chamber, first nozzle means positioned in said first bore and having a second bore communicating with said supply of coating material for discharging material from said supply along a first path, said first nozzle means having a discharge end projecting into said outlet, means for electrostatically charging the material in said second bore, a source of gaseous fluid under pressure, and conduit means interconnecting said source of fluid and said enlarged chamber for admitting said fluid thereto, the wall portion of said nozzle head and the discharge end of said first nozzle means forming second nozzle means for discharging said fluid along a second path intersecting said first path at an acute angle, said conduit means including at least one passage extending substantially tangentially into said enlarged chamber for producing a vortex of the fluid discharged from said second nozzle means, said first nozzle means discharging the charged material into said vortex to thereby atomize said material.

10. Apparatus for coating objects with a supply of liquid coating material, comprising a nozzle head defining a first bore having an enlarged cylindrical chamber adjacent one end thereof, said nozzle head including a wall portion having a circular edge between said enlarged chamber and said one end to form an outlet from said chamber, first nozzle means movably positioned in said first bore and having a second, coaxial bore communicating with said supply of coating material for discharging material from said supply along a first path, said first nozzle means including a discharge end projecting into the outlet formed by said circular edge, means for electrostatically charging the material in said second bore, a source of gaseous fluid under pressure, conduit means interconnecting said source of fluid and said enlarged cylindrical chamber for admitting said fluid thereto, the wall portion of said nozzle head and the discharge end of said first nozzle means forming second nozzle means for discharging said fluid along a second path intersecting said first path, said first nozzle means discharging the charged material into said fluid to thereby atomize said material, and means for moving said first nozzle means in an axial direction with respect to said first bore to vary the rate of discharge of said fluid therefrom.

11. Apparatus for coating objects with a supply of liquid coating material, comprising a nozzle head defining a first bore having an enlarged cylindrical chamber adjacent one end thereof, said nozzle head including a wall portion tapering to a sharp circular edge between said enlarged chamber and said one end to form an outlet from said chamber, first nozzle means positioned in said first bore for axial movement with respect thereto and having a second bore communicating with said supply of coating material for discharging material from said supply along a first path, said first nozzle means including a tapered end projecting into the outlet formed by said sharp circular edge, the degree of taper of said tapered end being different from that of said wall portion, means for electrostatically charging the material in said second bore, a source of gaseous fluid under pressure, conduit means interconnecting said source of fluid and said enlarged cylindrical chamber for admitting said fluid thereto, the tapered wall portion of said nozzle head and the tapered end of said first nozzle means forming a second nozzle means for discharging said fluid along a second path intersecting said first path, said first nozzle means discharging

the charged material into said fluid to thereby atomize said material, and means for moving said first nozzle means in an axial direction with respect to said first bore to vary the rate of discharge of said fluid therefrom.

12. Electrostatic spraying apparatus for coating objects with a supply of liquid coating material, comprising a nozzle head defining a first bore having an enlarged cylindrical chamber adjacent one end thereof, said nozzle head including a wall portion tapering to a sharp circular edge between said enlarged chamber and said one end to form an outlet from said chamber, first nozzle means positioned in said first bore for axial movement with respect thereto and having a second bore communicating with said supply of coating material for discharging material from said supply along a first path, said first nozzle means having a tapered end projecting into the outlet formed by said sharp circular edge and including an adjustable member movably disposed within said second bore for controlling the flow of material therethrough, the degree of taper of said tapered end being different from that of said wall portion, means for electrostatically charging the material in said second bore, a source of gaseous fluid under pressure, conduit means interconnecting said source and said enlarged cylindrical chamber for admitting said fluid thereto, the tapered wall portion of said nozzle head and the tapered end of said first nozzle means forming second nozzle means for discharging said fluid along a second path intersecting said first path, said first nozzle means discharging the charged material into said fluid to thereby atomize said material, and means mounted for rotation about the axis of said first bore and cooperating with said first nozzle means for moving the same in an axial direction with respect to said first bore, to adjust the size of the outlet between said tapered end and said wall portion and thereby vary the rate of discharge of said fluid therefrom.

13. Apparatus for coating objects with a supply of coating material, comprising a nozzle head defining a first bore having an enlarged cylindrical chamber adjacent one end thereof, said nozzle head including a wall portion having a sharp circular edge between said enlarged chamber and said one end to form an outlet from said chamber, first nozzle means movably positioned in said first bore and having a second bore communicating with said supply of coating material for discharging material from said supply along a first path, said first nozzle means having a discharge end projecting into the outlet formed by said sharp circular edge, means for electrostatically charging the material in said second bore to a high D.C. potential, a source of fluid under pressure, conduit means interconnecting said source of fluid and said enlarged cylindrical chamber for admitting said fluid thereto, the tapered wall portion of said nozzle head and the discharge end of said first nozzle means forming second nozzle means for discharging said fluid along a second path intersecting said first path, said conduit means including a plurality of passages extending substantially tangentially into said enlarged cylindrical chamber for producing a vortex of the fluid discharged from said second nozzle means, said first nozzle means discharging the charged material into said vortex to thereby atomize said material, and means for moving said first nozzle means in an axial direction with respect to said first bore to vary the rate of discharge of said fluid therefrom.

14. Electrostatic spraying apparatus for coating objects with a supply of liquid coating material, comprising a nozzle head defining a first bore having an enlarged cylindrical chamber adjacent one end thereof, said nozzle head including a wall portion tapering to a sharp circular edge between said enlarged chamber and said one end to form an outlet from said chamber, first nozzle means positioned in said first bore for axial movement with respect thereto and having a second bore communicating with said supply of coating material for discharging material from said supply along a first path, said first nozzle means having

a tapered end projecting into the outlet formed by said sharp circular edge, the degree of taper of said tapered end being different from that of said wall portion, means for electrostatically charging the material in said second bore to a high D.C. potential, a source of gaseous fluid under pressure, conduit means interconnecting said source of fluid and said enlarged cylindrical chamber for admitting said fluid thereto, the tapered wall portion of said nozzle head and the tapered end of said first nozzle means forming second nozzle means for discharging said fluid along a second path intersecting said first path, said conduit means including a plurality of passages extending substantially tangentially into said enlarged cylindrical chamber for producing a vortex of the fluid discharged from said second nozzle means, said first nozzle means discharging the charged material into said vortex to thereby atomize said material, and adjustment means mounted for rotation about the axis of said first bore and cooperating with said first nozzle means for moving the same in an axial direction with respect to said first bore, to adjust the size of the outlet between said tapered end and said wall portion and thereby vary the rate of discharge of said fluid therefrom.

15. Electrostatic spraying apparatus of the character set forth in claim 14, in which said nozzle head comprises an elongated housing having a rear wall at the end thereof opposite said wall portion, said first nozzle means including an abutment disposed within said housing, and resilient means compressed between said abutment and said rear wall for resisting rearward movement of said first nozzle means relative to said rear wall.

16. Apparatus for coating objects with a supply of liquid coating material, comprising a nozzle head defining a first bore having an enlarged cylindrical chamber adjacent one end thereof, said nozzle head including a wall portion tapering to a sharp circular edge between said enlarged chamber and said one end to form an outlet from said chamber, first nozzle means positioned in said first bore for axial movement with respect thereto, said first nozzle means having a second bore communicating with said supply of coating material and including a conical opening for discharging material from said supply along a first path, said first nozzle means having a tapered end projecting into the outlet formed by said sharp circular

edge and including an elongated pin member movably disposed within said second bore, the degree of taper of said tapered end being different from that of said wall portion, said pin member having a conical head positioned within said conical opening for controlling the flow of material therethrough, means for electrostatically charging the material in said second bore, a source of gaseous fluid under pressure, conduit means interconnecting said source of fluid and said enlarged cylindrical chamber for admitting said fluid thereto, the tapered wall portion of said nozzle head and the tapered end of said first nozzle means forming second nozzle means for discharging said fluid along a second path intersecting said first path at an acute angle, said conduit means including a plurality of passages extending substantially tangentially into said enlarged cylindrical chamber for producing a vortex of the fluid discharged from said second nozzle means, said first nozzle means discharging the charged material into said vortex to thereby atomize said material, and means mounted for rotation about the axis of said first bore and cooperating with said first nozzle means for moving the same in an axial direction with respect to said first bore, to adjust the size of the outlet between said tapered end and said wall portion and thereby vary the rate of discharge of said fluid therefrom.
